UNITED STATES PATENT OFFICE.

HARRY J. SEELY, OF LOS ANGELES, CALIFORNIA.

REFLECTOR.

Application filed October 10, 1921. Serial No. 506,746.

To all whom it may concern:

Be it known that I, HARRY J. SEELY, a citizen of the United States, residing at Los Angeles, in the county of Los Angeles and 5 State of California, have invented a new and useful Reflector, of which the following is a specification.

This invention relates to a reflector for headlights, one of the objects of the invention being to provide a structure that may be placed in the ordinary headlight casing whereby the reflecting surfaces may be adjusted to project the rays of light downwardly and forwardly as desired.

Another object is to provide a device of 15 this character in which the reflector is divided into two sections the two sections being adjusted independently.

A still further object is to provide a reflector which operates to illuminate or flood 20 with light the path of the automobile instead of focusing the light rays at some particular point in advance of the machine.

With these and other objects in view 25 which will appear as the description proceeds, the invention resides in the novel combination and arrangement of parts and in the details of construction hereinafter described and claimed, it being understood that slight changes may be made in the precise embodiment of the invention without departing from the spirit of the invention or sacrificing any of the advantages there- 30 of.

In the drawing forming a part of this 35 specification,

Figure 1 is a cross sectional view through an ordinary lamp casing the device forming the subject matter of this invention being 40 shown in position therein.

Figure 2 is a front elevation of the reflector supporting frames.

Figure 3 is a side elevation of the same and

Figure 4 is a plan view of one of the 45 frames and reflector carried thereby.

Referring to the drawings by characters of reference, the numeral 1 designates an ordinary headlight casing having the usual 50 lens 2 and lens retaining rings 3.

The reflector considered as a whole is of the usual parabolic shape but is divided along its horizontal median line into two sections 4 and 5, each section being provided

along its forward edge with a flange 6 and 7 respectively.

A frame 8 supporting the lower reflecting member 5 comprises a semi-circular ring 9, the extremities of the ring having rearwardly projecting arms 10, which closely follow the contour of said reflector. Near the center of the reflector the arms are bent as shown at 11, spaced slightly apart and extended parallel to form a seat 12 for a clip 13 which is designed to hold a lamp socket 14. A threaded stem 14' attached to the socket 14, is engaged by a thumb screw 14" for adjusting the lamp bulb to properly focus the light rays on the road. Frictional engagement of the clip 13 preventing rotation of the lamp socket while this adjustment is being made. Rearwardly of the seat 12 the arms 10 diverge to form attaching members 15, by which the frame member 8 is secured to the lamp casing. The lower reflector 5 is secured to the frame 8 by means of screws 16 which pass through apertures in the flange 7 and are screw threaded into openings 17 in the ring 9. A limited amount of vertical adjustment is possible in the reflector 5, by reason of an elongation of the openings 17', through which bolts or rivets 18 are passed to secure the frame 8 to the headlight casing.

The upper reflector section 4 is made fast 85 to a supporting frame 19 in the same manner that the lower reflector is secured to the frame 8. The frame 19 comprises a semi-circular ring 20 and arcuate arms 21 extending rearwardly from each end of said ring. The ends of the arms 21 are downturned to form a hinged connection 22 on the frame 8.

A screw threaded stem 23 is connected to the frame 19 and is engaged by a thumb 95 screw 24 which is mounted for rotation in an opening in the headlight casing.

Lugs 25 formed on the arms 10 and 21 respectively provide seats for compression springs 26 which exert pressure against the 100 frame 19 to prevent vibration of the device.

In attaching the reflector to a headlight casing the lower frame is adjusted to get the most desirable results from the rays of light reflected by the lower reflector, after 105 which the said frame is permanently fixed to the casing. Adjustment of the upper frame is then possible by means of the mem-

bers 23 and 24. In this way the light rays from the reflector may be directed downwardly and forwardly as desired.

Having thus described the invention what is claimed is:

1. In a device of the class described, articulate frames provided at their inner ends with rearwardly convexed arms, the arms of one frame being prolonged to form rearwardly extended fingers having attaching means; a lamp socket mounted on the said fingers; the arms of the other frame terminating in offset extensions which are pivotally connected to the arms of the first specified frame; and reflector sections mounted on the frames and on the arms thereof.

2. In a device of the class described; a pair of reflector sections; frames attached to said sections and conforming in shape to the periphery of the sections; arms extending rearwardly from the frames, the arms of one frame being pivotally connected to the arms of the other frame; a lamp socket holder carried by the arms of one frame and means for moving the socket with relation to the holder.

In testimony that I claim the foregoing as my own, I have hereto affixed my signature in the presence of two witnesses.

HARRY J. SEELY.

Witnesses:

M. H. HUGHES,
FRED GUYON.
